UNITED STATES PATENT OFFICE.

ALEXANDER P. POLANCHYCH, OF GIRARDVILLE, PENNSYLVANIA.

DESIGN FOR A COMB AND BRUSH HOLDER.

59,280.

Specification for Design.

Patented Oct. 4, 1921.

Application filed November 9, 1920. Serial No. 422,965. Term of patent 7 years.

To all whom it may concern:

Be it known that I, ALEXANDER P. POLANCHYCH, a citizen of Austria, residing at Girardville, in the county of Schuylkill and State of Pennsylvania, have invented a new, original, and ornamental Design for a Comb and Brush Holder, of which the following is a specification, reference being had to the accompanying drawing, forming a part thereof.

The figure is a plan view of the comb and brush holder showing my new design.

I claim:

The ornamental design for a comb and brush holder as shown.

ALEXANDER P. POLANCHYCH.
